UNITED STATES PATENT OFFICE

ARTHUR W. ZERBY, OF READING, PENNSYLVANIA

FROG FORMING INSERT FOR HOSIERY BOXES

Application filed April 9, 1929. Serial No. 353,823.

This invention relates to boxes for holding women's stockings and to certain detailed improvements upon the box disclosed in my Patent No. 1,728,385 of September 17, 5 1929. In this application for patent, I have shown a hosiery box having "frogs" as they are called, so arranged that when a pair of stockings is folded, the toe and heel portions of the stockings will be received and held in 10 the spaces designed to receive the toe and heel portions, while the leg portions of the stockings, if these stockings be properly folded, will lie in the box and abut against the adjacent ends of a pair of opposed frog 15 members, thus preventing sliding or rolling of the stockings to prevent the stockings from getting out of order or shape in the box, while at the same time providing for an attractive display of the folded stockings.

20 The present invention relates to the formation of an insert of light cardboard adapted to be disposed within the box and so formed as to provide lateral frogs and if desired a triangular toe frog so designed as 25 to hold the stockings in place as above stated.

A further object in this connection is to so form the insert that the frogs are formed integral with the cardboard of the insert and 30 cut out therefrom by means of suitable dies and folded up to form the frogs by means of suitable dies and further to so form this insert that it may be made of cardboard having only one highly finished face and to further so form the insert that the portion of 35 the pasteboard insert forming the frogs proper will have this finished face upon the exterior thereof.

Other objects will appear in the course of 40 the following description.

My invention is illustrated in the accompanying drawings, wherein:

Figure 1 is a plan view of a box having my improved insert applied thereto, the insert 45 being broken away;

Figure 2 is a section on the line 2-2 of Figure 1;

Figure 3 is a section on the line 3-3 of Figure 1;

50 Figure 4 is a plan view of the blank from

which the insert used in Figure 1 is made;

Figure 5 is a fragmentary plan view of the upper portion of a box having another form of insert therein and partly broken away;

Figure 6 is a fragmentary view of the 55 blank from which the insert shown in Figure 5 is made.

In Figure 1 I have illustrated an insert designated 10 which is formed of a single sheet of pasteboard having a substantially 60 finished face which is designed to form the exposed face of the insert. One face, for instance, of this pasteboard may be tinted or may have a highly enamelled or polished surface or may be otherwise ornamented, 65 while the reverse face of the stock may be unornamented or untinted.

The insert is designed to provide two frogs A disposed at the sides of the insert 70 at one end thereof, these frog portions A being associated with a triangular frog portion B, the opposite ends of the frog portions A forming abutments against which the folded legs of the stockings will bear, the ankles of the stockings and the toes and heels being 75 disposed between the frogs A and extending into the space between the frog B and the frog portions A. This insert is formed, as before stated, from a single sheet of light 80 cardboard.

In order to form the triangular frog portion B, the cardboard sheet is cut diagonally inward along the line 10 and then transversely at 10^a for a short distance and a slit 10^b 85 is formed extending upward and medially from the end of the slit 10^a. The cardboard is scored transversely along the line 11 to provide for folding down the portion 12 above this score. The cardboard is also scored on its inner surface as at 13, these scores extending downward and medially and intersecting each other and a parallel score upon the exterior face of the cardboard is formed at 14. These scores 11 and 13 define the triangular frog portion B.

The score 15 which extends upward from the slit 10 to the junction of the scores 13 forms a flap 16 adapted to be inserted behind the vertical lower wall of the triangular frog B as shown in Figure 1. Thus when this 100

portion of the insert has been folded as described, the triangular frog B will be completely formed.

It will be noted from Figures 1 and 6 that the upper edge of the flap which forms the frog B or B' is not disposed at right angles to the lateral edges of the insert or to the longitudinal axis of the insert or sheet but is disposed at less than a right angle and that the score line 11 is, of course, parallel to the upper edge 12 so that the axial center of the frog B, that is, a line extending from the base of the triangular frog and through the apex thereof is disposed at an angle to the longitudinal axis of the frog. This structure permits the insert to be made with great economy of material as there is no part of this frog which projects laterally out beyond the side lines of the sheet and further permits the lateral frogs A which are hereafter to be described to be disposed close to the ends of the triangular frog so that an insert may be formed provided with an upper triangular frog and two lateral frogs which are disposed close to the ends of the triangular frog for the purpose of holding women's stockings folded as shown in Figure 1.

Each frog portion A as shown in Figure 3 is formed with an outer depending wall a and an inner depending wall a' and a wall a² extending upward and outward to the corner of the insert. In order to form these frogs A from one sheet of material, it is necessary to punch out a transversely extending slot or cut out 19 in the cardboard which will intersect each of the frog portions A at the junction of the faces a² with the faces a', this cut or opening 19 being formed with triangular ends 19^a. As shown in Figure 4, the blank for this insert is transversely slotted inward as at 20. This slit 20 does not extend to the outside edge of the blank, but ends sufficiently from the outside edge of the blank to provide for the outside margin of the blank being longitudinally scored as at 21 so that the portion between this score 21 and the edge of the blank may be turned down to form the wall a. The portion forming the wall a is extended along the margin of the blank but separated therefrom by a slit 22 and this portion which forms the wall a³ closing the small end of the frog portion A is transversely scored so that the extremity a⁴ of this wall may be turned inward behind the wall a'. The wall a' is formed by longitudinally scoring the material on each side of the blank as at 23 and 24 so that this wall a' may be turned up to a vertical position and the wall a² is also formed by two angularly directed scores 25 and 26, the score 25 extending upward and outward from the edge of the blank.

The body of the blank 10 below the transverse slits 20 is formed to provide the marginal flanges 27 by scoring the edges of the

margins of the blank so that these may be turned upward to form walls or flanges fitting within the box so that the insert will be held firmly within the box itself.

It will be seen that when the marginal portions or walls a are turned to a vertical position that the walls a' and a² will also be turned to a vertical position and that this will tend to close the opening 19 or narrow it and that when the completed insert is placed within its box that the frogs will be supports with their walls in a position at right angles to the face of the box and be held rigidly in place so as to receive in the spaces between the frogs the folded stockings. It will be seen that the walls a' constitute abutments against which the relatively wide upper ends of the stockings will bear when the stockings are folded and that the ankle portions of the stockings will be received between the walls a' with the toes disposed over the opening 19 and the heels will extend in divergent directions. The pair of stockings will thus be held in folded condition against disorder and against any shifting action within the box and the stockings cannot get out of order and at the same time are well displayed when the box is opened.

In Figure 5 I show a modified form of insert having at one end a triangular frog B' such as previously described and adjacent this frog and on each side thereof the lateral frogs A'. These have outwardly diverging inner faces or walls but these walls do not intersect the upper corners of the insert but intersect the upper end of the insert.

The triangular frog B' is shorter than the insert instead of having a width approximately equal to the width of the insert as in Figure 1. The frog B' is formed in precisely the same manner as the frog B previously described and hence the same reference numerals have been applied to the walls and folds thereof. The only difference between the frog B' and the frog B is that the rear wall formed by the portion 12 of frog B' extends the entire width of the insert and beyond the ends of the frog B'.

The frogs A' are formed by transversely slitting the material of the insert or sheet 10 at 28. The inclined wall a² of the frog A' extends the whole length of the frog instead of only partially the length of the frog as in Figure 1 and hence there is no necessity of transversely slitting the insert 10 at 19 as previously described. Instead the blank is longitudinally scored at 25^a and 26^a for the whole length of the frog so as to form the inside wall a³ of the frog. The outside wall of the frog is formed by the longitudinally extending score 21^a whereby the outer margin may be bent into a position at right angles to the plane of the sheet and the frog is closed at its wider end by slitting the

blank at 22^a as heretofore described, this portion of the blank being then bent inward and the extreme end of this extension being angularly bent as at a⁴ so that it may be tucked inward behind the wall a². Otherwise than as above described, the blank for the insert is the same as that shown in Figure 4, the principal difference being that in the one insert, the lateral frogs A have inner parallel walls a' and then have walls diverging outwardly.

In the insert shown in Figure 5 the lateral frogs A' are formed with inner walls which extend in straight lines outward and toward that end of the insert having the triangular frog B'. In one case, it is necessary to provide the transverse cut-away portion 19. In the other case, it is not. Therefore, the insert shown in Figure 5 is cheaper to make than that shown in Figure 1 but it does not as securely hold the stockings against movement.

It will be seen that all of these inserts may be disposed within boxes, that they will form ornamental linings as it were for the boxes within which they are disposed, that by reason of the fact that the inserts are each formed with a frog having a squared leg engaging end or abutment that the stockings will be held in place against longitudinal shifting movement and that the lateral frogs will hold the stockings against lateral shifting movement, while at the same time the stockings are displayed in a particularly attractive manner.

Furthermore, the design for these inserts is such that the coated, ornamented or finished face of the cardboard sheet is displayed at all points and over all areas. These inserts may be readily formed by dies, and thus may be very cheaply and quickly made. After the blanks for the inserts have been cut and stamped or otherwise formed, they may be readily bent up for insertion within a hosiery box.

While I have illustrated two different forms of my invention, I do not wish to be limited to the exact details shown, as many of these might be changed or varied within the scope of the appended claims without departing from the spirit of the invention.

It is in order to show that the blanks may be varied to some extent that I have illustrated two different forms of my invention. It is also to be particularly noted that in both forms of insert, each lateral frog is defined at its upper and lower ends by a transverse opening or slit. In Figure 4, there is a space above the pointed end of the left hand frog while the right hand frog at its upper end is defined by an opening which extends into the cardboard. In Figure 6, there are inwardly extending spaces on each side which extend in from the outer margins of the cardboard blank toward the triangular frog B',

while the lower end of each frog B is defined by the slit 28. The lateral frogs are, therefore, separated from the body blank at their upper and lower ends so that they may be bent upward.

By using an insert of the character described in a hosiery box, the bottom of the box proper can be made of uncoated or unglazed cardboard. Where no insert is used, the coated or glazed cardboard is necessary in order to form the box. With my construction, it is not necessary to glue or paste the frog in the box and no locks are necessary in order to hold the frogs in position. Further by means of this improved insert, the toe, heel and leg portions of hosiery can be displayed while in the box so that the customer can see all three of these portions without unfolding the stocking which is not the case in the present manner of displaying stockings in boxes.

I claim:—

1. An insert for hosiery boxes formed of a single sheet of cardboard, the sheet at one end having a diagonal cut extending inward and medially from the adjacent end of the sheet and a diagonal score extending inward and medially and converging toward the end of the cut, the area defined by said cut and score having two converging scores parallel to the first named cut and score, the upper end of the sheet having a transversely extending score parallel to the edge thereof, the areas defined by the first named scores forming the inner walls of an integral triangular frog, the area defined by the last named score and the end edge of the sheet forming the outer wall of the frog the end edge of the sheet forming the upper edge of the frog extending transversely of the sheet at an angle less than a right angle to the longitudinal axis of the sheet.

2. An insert for hosiery boxes, the insert having a triangular frog at one end, the frog being formed by an integral flap connected to the body of the sheet along a diagonal inwardly and medially extending score, the flap being separated from the body of the sheet opposite the score by an inwardly and medially extending cut, the cut being extended upward from the end of the score, the area defined by said cut and the score having two inwardly diverging scores parallel to the first named cut and score and intersecting at their junction with the upwardly extending portion of said cut, there being a score extending inward and laterally from said point of convergence to said cut whereby to form a flap engageable beneath the first named scored portion, the upper end of the sheet having a transversely extending score parallel to the upper edge thereof, the area defined by the last named score and the end edge of the sheet forming the outer upstanding wall of the frog, the upper edge of the

flap forming the frog and the last named score of the flap being disposed at less than a right angle to the longitudinal axis of the sheet.

- 15 3. An insert for hosiery boxes for containing women's stockings, the insert being formed of a single sheet of material, the insert at one end being formed to provide an upstanding integral triangular frog having 10 its apex inward and the sheet being formed to provide two lateral upstanding frogs, each extending from a point intermediate the ends of the sheet to a point adjacent the lateral ends of the triangular frog, the lower ends 15 of the lateral frogs remote from the triangular frog being defined each by a cut extending at right angles to the length of the sheet and outward toward the adjacent edge of the sheet, the cut then extending longitudinally 20 parallel to the edge of the sheet and away from the frog and then outward to form a free tab, the sheet on each side having a score forming a continuation of the longitudinal portion of said cut, the sheet on each side of 25 its middle having two parallel scores intersecting the inner portion of the transverse cut and extending thence to the end of the sheet having the triangular frog, said tab when the frog is elevated being extended 30 across and closing that end of the corresponding lateral frog remote from the triangular frog.

4. An insert for hosiery boxes containing women's stockings and formed of a single 35 sheet of material, the sheet being formed to provide an upstanding integral triangular frog adjacent one end of the sheet having its apex extending inward, the sheet having a longitudinally extending slit on each side of 40 the sheet and a longitudinal score forming a continuation of the slit, the slit and score being spaced from the adjacent edge of the sheet, a transverse slit extending inward from the junction of the longitudinal slit with the 45 score, two spaced longitudinal scores extending from the inner portion of the transverse slit, then extending at an angle longitudinally and laterally to one end of the sheet, the outer score intersecting the adjacent end of 50 the first named score, the sheet having a transverse opening terminating at each end in a V-shaped portion, the apex of which intersects the inner score at the junction of the longitudinal with the outwardly angled portions of the scores.

In testimony whereof I hereunto affix my signature.

ARTHUR W. ZERBY.
